JAMES WATERS, OF MINNEAPOLIS, MINNESOTA.

Letters Patent No. 87,992, dated March 16, 1869.

IMPROVEMENT IN STEAM-GENERATOR GAUGE-COCKS.

The Schedule referred to in these Letters Patent and making part of the same.

To all whom it may concern:

Be it known that I, JAMES WATERS, of the city of Minneapolis, county of Hennepin, and State of Minnesota, have invented a new and useful Improvement in Gauge-Cocks for Steam-Boilers; and I do hereby declare that the following is a full, clear, and exact description thereof, which will enable those skilled in the art to make and use the same, reference being had to the accompanying drawing, forming part of this specification, in which—

Figure 1 is a longitudinal sectional view of my invention.

The object of my invention is to produce a gauge-cock that shall, with certainty, tell the exact height of the water in the boiler, from the top of the flues to the top of the boiler.

A is the main stock, which screws into the boiler.

B, the pipe which discharges water or steam from the boiler.

C, the pipe which receives the water or steam from the inside of the boiler.

D, the handle, with which the cock is operated.

E, valve.

F, the pin, to stop up the end of the valve-case.

G, a guard packing-ring, between the valve-case and the stationary stock A.

H, holes through the valve-case, to let water or steam out to the discharge-pipe B.

I, stuffing-box.

K, valve-case.

L, valve-seat.

Operation.

The pressure in the boiler will press the valve-case K against the guard-ring G, making a tight joint, and will also press the valve on to the valve-seat L. This makes all tight. Take hold of handle D, pull out on its outer end, which will throw the valve off its seat, and the steam or water will pass out through the outlet B. Then turn the handle D till the end of inlet C shall strike the surface of the water, and you will know when the water is in the boiler. The handle D being just as long as the inlet-pipe C, and standing in the same direction, of course the outer end of the handle D will show exactly when the water is in the boiler.

What I claim as my invention, and desire to secure by Letters Patent, is—

A gauge-cock, consisting of stock A, valve-case K, valve E, valve-seat L, inlet C, and lever D, arranged substantially as described.
